ABSTRACT

An assembly of articulated panels is slidably mounted in tracks on a door frame which interconnect with overhead tracks in an enclosure, the door frame tracks being separable from the overhead tracks and the frame being hinged in a doorway for horizontal opening of the frame when the panels are closed. Latch means is provided which prevent opening movement of the frame except when the panels are completely closed.

VERTICALLY SLIDING DOOR MOUNTED IN HORIZONTALLY PIVOTED FRAME

BACKGROUND OF THE INVENTION

Vertically acting roll-up doors have been used for many years for various enclosures such as building structures and mobile vehicles including trucks and trailers. The doors have advantages over the conventional hinged door in that they are readily adaptable to relatively simple operating means and may cover a large area without the necessity for providing swinging space or the structural requirements for a conventional hinged door.

However, while the various advantages, including the relative ease of operation, are present, such doors, particularly in vehicular use, suffer from disadvantages including that cargo may become displaced and engage the door making it difficult or impossible to raise the same. Furthermore, if the doors become covered with ice and snow, they cannot be raised when they reach their destination except by thawing, which frequently results in substantial delays.

On present day roll-up doors, when difficulty is encountered in raising them due to conditions such as those mentioned, the practice is to employ a pry bar or a fork lift truck to raise the door. Not only are such procedures time consuming and costly, but are likely to misalign and damage the door, requiring repairs before the vehicle can be used.

An inherent disadvantage accompanying roll-up doors is that due to the necessity for the roller mounting at the sides, the width of the doorway is less than that of the enclosure. In some situations this may prevent, or cause difficulty in, the hauling of merchandise which the vehicle would otherwise be able to accommodate.

A further disadvantage of ordinary roll-up doors is that these are usually shipped to the equipment manufacturer only partially assembled and require substantial time to complete the assembly and install.

SUMMARY OF THE INVENTION

The present invention is a two-way door assembly for an enclosure such as a truck body and includes a door frame swingably connected along one side of the opening to the enclosure, and such door frame is provided with a plurality of hinged panels carried within tracks on the door frame. The tracks on the door frame are in alignment with tracks within the enclosure so that when the door frame is closed, the panels can be moved upwardly from a generally vertical position to a generally horizontal position within the enclosure. A safety latch is provided to prevent swinging of the door frame when the door panels are not fully closed.

OBJECTS OF THE INVENTION

Accordingly, it is an object of the invention to provide a door and door frame assembly in which the door includes a plurality of hingedly connected panels adapted for sliding roll-up operation or the

frame is adapted to swing about pivots disposed along a generally vertical axis.

Another object of the invention is to provide a safety lock for locking the frame in the doorway and which may be unlocked only when the panels are in closed position.

A further object of the invention is to provide a ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ⁴⁹⁷⁵ ⁴⁹⁸⁰ ⁴⁹⁸⁵ ⁴⁹⁹⁰ ⁴⁹⁹⁵ ⁵⁰⁰⁰ ⁵⁰⁰⁵ ⁵⁰¹⁰ ⁵⁰¹⁵ ⁵⁰²⁰ ⁵⁰²⁵ ⁵⁰³⁰ ⁵⁰³⁵ ⁵⁰⁴⁰ ⁵⁰⁴⁵ ⁵⁰⁵⁰ ⁵⁰⁵⁵ ⁵⁰⁶⁰ ⁵⁰⁶⁵ ⁵⁰⁷⁰ ⁵⁰⁷⁵ ⁵⁰⁸⁰ ⁵⁰⁸⁵ ⁵⁰⁹⁰ ⁵⁰⁹⁵ ⁵¹⁰⁰ ⁵¹⁰⁵ ⁵¹¹⁰ ⁵¹¹⁵ ⁵¹²⁰ ⁵¹²⁵ ⁵¹³⁰ ⁵¹³⁵ ⁵¹⁴⁰ ⁵¹⁴⁵ ⁵¹⁵⁰ ⁵¹⁵⁵ ⁵¹⁶⁰ ⁵¹⁶⁵ ⁵¹⁷⁰ ⁵¹⁷⁵ ⁵¹⁸⁰ ⁵¹⁸⁵ ⁵¹⁹⁰ ⁵¹⁹⁵ ⁵²⁰⁰ ⁵²⁰⁵ ⁵²¹⁰ ⁵²¹⁵ ⁵²²⁰ ⁵²²⁵ ⁵²³⁰ ⁵²³⁵

balance spring is mounted. Such spring is connected to a reel 17 with lines 18 extending therefrom.

In order to seal the frame against leakage between it and the sides of the vehicle, a gasket 20 is provided having a portion 21 which engages the corner of the frame when it is closed and the inside wall of the enclosure as indicated in FIG. 4. The gasket 20 also has a portion 22 which extends inwardly to engage the panels of the sliding door, as will be described.

The frame is pivotally mounted at the side of the enclosure by a plurality of hinges 25 which are spaced vertically of the doorway and the frame and have pins 26 at the outer side of the walls W3.

As indicated in FIG. 3, the outer edge 27 of the floor W2 has a rounded portion or radius 28 for engagement with the rearward rounded portion or radius 29 of the frame sill in order that as the door is closed on the hinges these two rounded portions may engage and cooperate if necessary to align the door.

In order to hold the frame in closed position, a latching means 40 is provided at the right side which includes a vertical bar 41 having horizontal extensions 42 at its ends, the bar mounted by loops 43 on the frame which permits shifting of the bar so that its outer ends may be locked to engage under flanges or lips 45 mounted on the frame of the enclosure.

In order to mount the slideable door on the frame, left and right roller trackways 50 having inwardly inclined upper portions 51 are mounted by brackets 52 which are connected to the left and right frame members 11 and 12.

The slideable door includes a plurality of interconnected panels 60. The panels are connected together by hinge members 61 which may be of the type indicated in FIG. 9 having leaves 62 and 63 connected to adjacent panels and to each other by a hinge pin 64. As illustrated in FIGS. 4, 8 and 9, each of the hinges 61 adjacent to the ends of the panels 60, includes a pair of upstanding tangs 65 terminating in bearings 66 in which a shaft 67 is rotatably mounted. A roller 68 is mounted on one end of the shaft 67 and is held in spaced relation to the bearings 66 by a spacer 69. The rollers 68 are received within the trackways 50 and are adapted to guide the door when the door panels are moved up and down.

Mounted within the enclosure are horizontally extending channel track members 80 having downwardly inclined end portions 81 which, when the door is in closed position, are aligned with the inwardly inclined end portions 51 of the track members 50 on the door frame. In order to facilitate alignment of these end portions when the door is being closed on its hinges, a bracket 84 is provided having a lower guide plate 85 and an upper guide plate 86 with a diverging lip 87 which guides the portion 51 of the track into position.

When the panels are in completely closed position, as indicated in FIG. 1, they may be held by latch means 90 which includes a handle portion 91 and a locking portion 92 mounted on pivot 93 and which engages a keeper 94 in the sill of the frame.

A handle 96 is provided on the lower panel to assist in raising and lowering the panels and a handle

97 is provided on the right frame to assist in opening and closing the door on the hinges.

It is important that no effort should be made to open the door on the hinges unless the panels are in the completely closed position, otherwise damage to the trackway and the panels is likely to occur. In order to prevent inadvertent movement of the frame about the hinge when the panels are not completely closed, an automatic safety interlock is provided as indicated in FIGS. 5-7. The interlock has an operating member or bell crank lever 100 which has an arm with a roller 101 that extends above the jamb 14 and is positioned for engagement by the lowermost panel when the latter is closed against the jamb. The lever has a pivot 102 and an operating leg 103. The leg 103 engages an abutment 104 mounted on a rod 105 which is slidably in apertures in spaced blocks 106, 107 in the jamb and engageable with an aperture in block 108 in the side of the vehicle. Spring 110 is coiled about the shaft intermediate the blocks 106 and 104 and urges the shaft 105 towards closed position as indicated in FIG. 5. When the slideable door is in raised position, therefore, the lock will be in the position of FIG. 5 thereby preventing any movement of the frame about the hinges 30. When the slideable door is closed, however, engagement of the lowermost panel moves the lever 100 to the position of FIG. 6 in which leg 103 shifts the shaft 105 to the left in order to retract it from the block 108 in the vehicle frame, thereby freeing the frame.

In the operation of the device, when the trailer is in use, the articulated panels 60 are locked to the frame 10 by the latch means 90 and the frame 10 is locked to the side wall W4 by the latch mechanism 40. When it is desired to open the rear door of the trailer by raising the articulated panels 60, the latch mechanism 90 is operated to release the locking portion 92 from the keeper 94 after which an upward force can be applied to the handle 96 so that the rollers 68 will move upwardly within the tracks 50 and through the inclined portions 51 and 81 onto the generally horizontal track 80 within the truck body. As soon as the articulated panels are moved upwardly a short distance, the spring 110 will cause the rod 105 to be extended into the orifice within the block 108 so that the frame cannot be moved. When the articulated panels are fully raised, the space defined by the frame 10 will be open so that the cargo can be placed in or removed from the trailer. After the loading or unloading has been completed, the articulated panels are moved downwardly through the tracks toward closed position. As the panels approach the sill 14, the lowermost panel will engage the roller 101 and pivot the bell crank lever 100 about the pivot 102 and cause the rod 105 to be retracted from the block 108. Thereafter the latch mechanism 90 is operated to lock the panels to the frame.

In the event that a larger opening is required, or if the cargo has shifted so that portions of the cargo are in engagement with the articulated panels and prevent ready movement thereof, the latch mechanism 40 can be operated to unlock the frame from the wall structure of the trailer, after which the frame with the articulated panels thereon can be swung about the hinge pins 26 through approximately 270° of rotation.

until the door is substantially abutting the side of the trailer, as illustrated in phantom in FIG. 1. After the loading or unloading has been completed, the door is swung to closed position and the latch mechanism 40 is operated to lock the door closed.

I claim:

1. A two-way door assembly for mounting on wall structure defining an enclosure with an opening therein, said assembly comprising a frame, hinge means mounting said frame on said wall structure adjacent to the opening, first track means having a lower portion mounted generally vertically on opposite sides of said frame, the upper portion of said first track means being disposed out of the plane of said lower portion, second track means mounted generally horizontally on said wall structure in alignment with the upper portion of said first track means, a plurality of articulated panels hingedly connected together, roller means carried by said panels and engageable with said first and second track means, first lock means for locking said panels to said frame, second lock means for locking said frame to said wall structure, third lock means operable by said panels for automatically locking said frame to said wall structure when the panels are in a raised position and for unlocking said frame from said wall structure when the panels are in a lowered position, and means for sealing said panels to said frame when said panels are in a lowered position, whereby said door frame can swing about said hinge means when said second and third lock means are released,

and said panels can be moved along said track means when the first lock means is released.

2. In a two-way door assembly for mounting on wall structure defining an enclosure with an opening therein, said door assembly including a frame hingedly mounted on said wall structure adjacent to the opening, first track means carried by said frame, second track means located within said enclosure, a plurality of articulated panels carried by said first track means and which can be selectively moved to said second track means when said tracks are adjacent to each other; the improvement comprising lock means carried by said frame to prevent swinging movement of said frame about its hinges when said articulated panels are raised, said lock means comprising latch means slidably carried by said frame, means urging said latch means outwardly of said frame and into locking engagement with said wall structure, operating means engageable by said panels for retracting said latch means out of engagement with said wall structure when said panels are entirely within said first track means.

3. The structure of claim 2 in which said operating means includes lever means swingably mounted on said frame, a first portion of said lever means engaging said latch means, a second portion of said lever means located in a position to engage a portion of said panels, whereby movement of said articulated panels to closed position causes said lever means to swing about its pivot and move said latch means out of engagement with said wall structure.
